SAFETY RAZOR

Glenn T. Randol, Mountain Lake Park, Md.

Application September 4, 1952, Serial No. 307,855

17 Claims. (Cl. 30—62)

Generally, the present invention relates to a novel safety razor construction for use with expendable blades of the type having a single cutting edge opposite an unsharpened butt edge.

More specifically, this invention pertains to a novel razor construction of the "injector" type, being so characterized because a blade may be inserted and removed endwise by lateral movements of a support structure therefor, and which is movable relatively to the handle and contains the blade during a shaving or unloading operation.

In regard to safety razors of various types, considerable attention has heretofore been directed to the personal injury factor incident to the placement and subsequent removal of an expandable blade. As a result, a number of loading devices and pre-packed blade-dispensing cartridges have been devised for blade placement, but insofar as I am aware, blade removal for cleansing and re-use or for discarding purposes, continues to be a chore fraught with the risk of personal injury.

Further, the devices under consideration are not reloadable, so that after the supply of blades therein contained has been exhausted, the cost of another cartridge must be added to that of new blades.

The primary object of the present invention is to provide a razor of the "injector" type which incorporates means for the safe insertion and removal of blades without necessarily requiring the use of an accessory.

To this end, the instant construction provides a side opening through which a slidably and pivotably mounted platform may be moved in one direction to project beyond one end of the razor head, where it is automatically supported in such position for the easy placement and removal of a blade. Means are provided on the platform for maintaining a deposited blade in place as the platform is retracted in the opposite direction to bring the blade into effective shaving position. In the latter position, a notch cooperates with an arm integrally formed on the platform for preventing the fortuitous displacement of the latter and the blade thereon, said arm being seated and so maintained in the notch aforesaid by the upwardly biasing action of a leaf spring.

The razor head comprises a substantially U-shaped frame rigidly secured to the upper end of a handle, and is angularly disposed forwardly relative to the latter. The frame features an elongated substantially semi-circular section which serves a dual purpose. That is to say, said section provides a slideway for the reciprocable blade-supporting platform, and also provides a pivotal connection therefor, as will appear. Said frame also includes a pair of longitudinally spaced depressions on the rearward portion of an upper resilient segment thereof, which depressions are adapted to enter into a pair of similarly spaced openings provided, for example, in the reinforcement strip, when so equipped, of the blade whenever the platform aforesaid is manipulated from a loading to a shaving position.

Details of construction not hereinbefore referred to, additional features and advantages which the invention provides, and the manner in which the invention achieves its objectives, will be apparent from the detailed description to follow with reference to the accompanying drawings.

In the drawings:

Figure 1 is a top plan view of a safety razor constructed in accordance with the principles of the present invention, and having a blade mounted therein in shaving position;

2

Figure 2 is a vertical sectional view taken approximately on the line II—II of Figure 1;

Figure 3 is a rear elevational view of the razor, the lower portion of the handle being broken away;

Figure 4 is a top plan view, partly in section and taken on the line IV—IV of Figure 2, the blade and its supporting platform however, being shown in a laterally projected position relative to the Figure 1 and 2 position thereof;

Figure 5 is a vertical sectional view taken substantially along the line V—V of Figure 2; and

Figure 6 is a perspective view of the movable blade-supporting platform per se, particularly illustrating a pair of upstanding blade retaining pins formed thereon.

Referring to the drawings:

The razor construction of the present invention is indicated generally by the reference numeral 10. Broadly, the illustrated structure includes a blade-receiving and supporting platform generally designated 12, which is por-

trayed particularly in Figure 6; a substantially U-shaped frame generally designated 14 for hingedly and slidably supporting said platform; a handle 16 formed of plastic or other suitable material; and a bracket 18 surmounting said handle to which the frame 14 is rigidly secured as by a pair of rivets, shown especially in Figures 3 and 5.

The platform 12 is of substantially rectangular configuration, and includes a flat main body portion 20 which terminates at the rear in an upwardly projecting flange segment 22, and at the front in a reversely bent approximately circular segment 24. As will appear, the segment 24 constitutes an elongated pivotal or hinge mounting for the platform.

Numerical 26 designates a rearwardly projecting arm which merges into the flange 22 adjacent to what will be termed the left end of the platform. The arm 26 terminates in a thumbpiece 27 the upper surface of which is preferably knurled as shown. At the right end, the body portion 20 of said platform has formed therein a semi-circular recess 28, the provision of which serves to facilitate blade mounting and removal, as will appear. Adjacent the left and right ends of platform 12 and forwardly located at a predetermined distance from flange 22, are two upstanding pin elements 30 which, as will be explained, cooperate with said frame 14 in the disposition of a blade for effective shaving operations. As Figure 6 demonstrates, the free end of each pin 30 is preferably rounded.

The frame 14 includes a lower base segment 32; an upper resilient segment 34 generally co-planar therewith; and a web segment 36 connecting the segment 32 with an upwardly offset portion 38 of the segment 34, as best seen in Figure 2. The frame 14 is angularly disposed forwardly with respect to the handle 16, and is rigidly secured to the bracket 18 as previously stated, and as the drawings clearly demonstrate.

With attention directed particularly to Figures 2 and 4, it is noted that the forward end of the base segment 32 terminates in an upwardly disposed blade rest portion 40 which is co-planar therewith, and is provided with a guard lip 42 along its forward longitudinal edge, and an elongated slot 44 rearwardly adjacent thereto for discharging beard-laden lather during a shaving operation.

Numerical 46 designates a pair of lateral web portions interconnecting the base segment 32 and the blade rest 40, said webs being co-extensive laterally with the frame 14. It is noted however, with particular reference to Figures 2, 3 and 4, that inwardly of the left and right marginal edges 48 and 50 of the frame 14, the base segment 32 is cut-out or slotted as at 52, whereby to provide in conjunction with the adjacent portion of said webs, an elongated substantially semi-circular section 54.

The free marginal longitudinal edge 56 of the upper segment 34 is preferably downwardly inclined as seen to best advantage in Figure 2. And as most clearly shown in Figures 1 and 5, said upper segment has formed therein a pair of longitudinally spaced downwardly extruded depressions or holes 58. Formed in the web segment 36 is an elongated slot 60 through which the arm 26 projects as best seen in Figures 3 and 4. The right end of said slot terminates in an upwardly offset notch 62 as illustrated in Figure 3. It is noted at this point, that the slot

60 is of sufficient width to freely accommodate slight vertical movements of the arm 26.

Numer 64 designates a leaf spring of the configuration best seen in Figure 5. There it is also noted that said spring is rigidly secured medially to the upper surface of the base segment 32 by means of the same fastening elements, such as the two rivets, which secure the frame 14 to the bracket 18.

The type of blade for use with the hereinbefore described safety razor construction is clearly portrayed in Figure 4, and designated 66. Said blade includes a cutting edge 68 opposite an unsharpened butt edge 70, the latter being an arcuate segment of a reversely bent reinforcement strip 72 with which the type of blade under consideration is ordinarily provided, but not a requisite since the longitudinally spaced depressions or holes as at 74 may be impressed directly in the blade proper thus eliminating the reinforcement strip.

Formed in the reinforcement strip 72, is, for example, a pair of the longitudinally spaced openings 74, the spacing corresponding to that of the extruded depressions 58 in the upper segment 34 of frame 14. Intermediate the butt and cutting edges of the blade 66, two notches 76 are indented along the side margins of said blade. These notches are preferably minutely larger than the diameter of the upstanding pins 30 incorporated in the platform 12 for reasons to be explained.

Although it is believed that from the preceding detailed description augmented by an inspection of the drawings, a comprehensive understanding of the invention may be had, a brief explanation of what will be termed a shaving cycle is presented as follows:

Assuming that the razor 10 has been unloaded following a previous shaving cycle, the platform 12 will be in its fully retracted position exhibited in Figures 1 and 3. In other words, the arm 26 is locked in the offset notch 62, the platform 12 being biased upwardly by the leaf spring 64 in blade clamping position.

Loading the razor is a simple procedure. Downward manual pressure is first applied to the thumb-piece 27 to swing the platform 12 downwardly about its pivotal mounting 24, 54 against the upward biasing force of the leaf spring, until the arm 26 engages the lower longitudinal edge of slot 60. Thereupon the platform 12 is manually moved to the right (Figure 4) until the arm 26 strikes against the right end edge of said slot, the pivot segment 24 sliding along the inner surface of the semi-circular frame segment 54. It is to be observed that should a release of manual pressure on the thumb-piece be had at any point of platform movement between the extreme positions thereof, the upward biasing force of leaf-spring 64 would automatically effect a locking of said platform in the position it concurrently occupies.

With the major portion of the platform 12 projecting beyond the right end 50 of the frame as in Figure 4, a blade 66 is now manually deposited thereon as shown, the pins 30 projecting upwardly through the slots 76, the butt edge 70 adjacent to the upstanding flange 22, the left corner portion of the blade adjacent the cutting edge 68 being supported on the rest portion 40 of the frame, and the right extremity of leaf spring 64 bearing against the underside of the blade support 12. The recess 28 facilitating placement and removal of the blade, as should be apparent.

With the blade in position thereon, the platform 12 is now retracted to the left by means of the thumb-piece 27 until the arm 26 strikes against the left end edge of slot 60. As contact is made, thumb-piece 27 is released whereupon leaf spring 64 swings the platform upwardly about its pivotal mounting to automatically actuate arm 26 into notch 62, thus locking the platform against fortuitous movement. Simultaneously, the blade 66 is automatically maneuvered into and clamped in effective cutting position by the camming action between the depressions 58 and blade openings 74 and the biasing action of leaf spring 64, respectively. It is noted that the camming action referred to is facilitated and accommodated by the slight clearance which obtains between the pins 30 of the platform 12, and the notches 76 in the blade.

Figures 1 and 2 clearly demonstrate the relative disposition of the parts during the shaving operation which follows. The inclined free marginal portion 56 of the resilient frame segment 34 bears against the longitudinal blade surface adjacent the cutting edge 68 thereof, thus

cooperating with the depressions 58 to stabilize the blade in clamped shaving position.

Following the shaving operation, platform 12 is again moved to its projecting Figure 4 position in the manner previously described, for easy removal of the blade as by grasping between the thumb and finger the end portion thereof exposed by recess 28.

The illustrated and thus far described embodiment of the invention may obviously admit of slight modifications in certain respects without departing from the novel concepts thereof. Thus, it should be manifest that the illustrated notch 62 could be dispensed with and rely solely on the upward biasing effect on the arm 26 into engagement with the upper edge of the slot 60 to releasably stabilize the platform 12 in the position desired.

In view of the foregoing, it should be apparent that my invention discloses a safety razor construction of the "injector" type adapted to efficiently achieve its objectives. It is simple in design, and easy to manipulate without risk of personal injury during the placement and removal of blades.

Further discussing the operative characteristics of the disclosed novel razor construction, it is desired to emphasize that the full length of the blade cutting edge 68 is utilizable to facilitate shaving in inaccessible facial portions such as about the nose and lips; and that the razor head and contained blade may be readily and thoroughly rinsed of beard laden lather singlehandedly during or upon completion of a shaving operation, particularly where a blade is retained for subsequent use since either the thumb or forefinger of the hand clasping the handle 16 can be used on the thumbpiece 27 to project the blade from the frame to enable drying the exposed cutting edge as by wiping with the free hand, without disturbing the blade proper in its "loaded" position on the platform 12.

It is to be understood that the invention contemplates all structural modifications and equivalents which may fall within the scope of the claims appended hereto.

40 I claim as my invention:

1. A razor construction including a handle, an open-ended frame rigid with one end of the handle, a blade receiving and supporting platform pivotally and slidably mounted in the frame, means for manually moving said platform in one direction to a first position wherein the major portion thereof projects beyond the confines of the frame, and for thereafter moving said platform in the opposite direction to a second position wherein all portions thereof are located within the confines of said frame, and means for yieldingly maintaining said platform in its first and second positions, and in any position therebetween.

2. A razor construction including a handle, an open-ended frame rigid with one end of the handle, a blade receiving and supporting platform pivotally and slidably mounted in the frame, means for first manually moving said platform in one direction to a position wherein the major portion thereof projects beyond the confines of the frame, and for thereafter moving said platform in the opposite direction to a position wherein all portions thereof are located within the confines of said frame, and leaf spring means for constantly biasing said platform toward the overlying segment of said frame.

3. The razor construction defined in claim 2, and means on the platform cooperating with means provided on a blade deposited thereon in the projected position thereof for properly positioning the blade on said platform.

4. The razor construction defined in claim 2, plus means on the frame cooperating with means provided on a blade supported on said platform for automatically maneuvering said blade into shaving position and clamping the same therein when the platform is biased as aforesaid after all portions thereof are positioned within the confines of said frame.

5. A razor construction including a handle, a substantially U-shaped frame rigidly mounted on the upper end of the handle in forwardly angular disposition relative thereto, a platform for supporting a blade in effective shaving disposition within said frame, an elongated reversely bent approximately circular segment on the body portion of said platform and a complementary elongated substantially semi-circular segment on the base portion of said frame to provide a combined pivotal and slidable mounting for said platform, and manually engageable

means on the platform for selectively moving same outwardly and inwardly with respect to said frame along the combined pivotal and slidable mounting thereof aforesaid.

6. The razor construction defined in claim 5, wherein the recited platform for supporting a blade is of a substantially rectangular configuration, and includes in addition to said approximately circular segment: a flat body portion whereto said blade lies; an upwardly projecting flange adjacent to which the butt edge of the blade is positioned; a pair of longitudinally spaced pins which project upwardly through similarly spaced slots indented along the side marginal edges of the blade; a semi-circular recess formed in said body portion along one end thereof for facilitating the placement and removal of blades; and the recited manually engageable means which comprises a rearwardly projecting arm merging at one end into said flange, and terminating at its opposite end in a thumb-piece the upper surface of which is knurled.

7. The razor construction defined in claim 5, in combination with means provided on the frame for cooperating with the recited manually engageable means to limit the outward and inward movements of the platform, and for releasably locking the latter in its inward position.

8. The razor construction defined in claim 5, in combination with a leaf spring mounted on said frame for constantly biasing the recited platform toward the overlying segment of said frame about the combined pivotal and slidable mounting thereof.

9. In a razor construction of the character described, the combination of: a handle supported open-ended frame; a blade receiving and supporting platform pivotally and slidably mounted in said frame; a manually engageable element integral with the platform for sliding said platform laterally in one direction to a position wherein the major portion thereof projects beyond one end of said frame for the reception of a blade, and for thereafter retracting said platform and the blade thereon in the opposite direction to dispose said blade in effective shaving position; means on the frame for limiting the movements of said platform in both directions and for releasably locking the platform in the blade-effective shaving position; and means mounted on the frame for applying upward pressure against the underside of the platform to clamp the blade in said shaving position.

10. In a razor construction of the character described, the combination defined in claim 9, and means on the uppermost segment of said frame inter-engageable with means on the surface adjacent the butt edge of the blade for maintaining the latter in said effective shaving position.

11. In a razor construction of the character described, the combination defined in claim 9 wherein the means for limiting the movements of and for releasably locking the platform include: an elongated slot provided in a

web segment of said frame through which said manually engageable element projects; and an upwardly offset notch formed at one end of said slot into which said element is biased, when in registry therewith, by the means mounted on said frame.

5 12. In a razor construction of the character described; the combination defined in claim 9, and a downwardly inclined longitudinal marginal edge portion on the uppermost segment of said frame to stabilize the blade during a shaving operation.

13. The combination with a razor blade having a single cutting edge of a blade holder of substantially U or loop cross section adapted to receive such blade endwise into

15 effective cutting position between the forward longitudinal confronting end surfaces of the legs thereof with the blade proper spanning substantially the space defined between the legs, means for supporting said blade within the blade holder comprising a planar portion integral with and forming the forward portion of one of the legs and a member connected to the interior of said one leg for pivotal and slidable movement with respect thereto, said member being pivoted into normally co-planar position with respect to the aforementioned planar portion

25 of the said one leg, means for continuously biasing said member toward its normal position, and a manually-operated element for pivotally and slidably moving said member and blade relatively to the blade holder in opposition to the biasing force of said last-named means.

30 14. The combination of claim 13 including means cooperating with said manually-operated element for locking the said member and blade against slidable movement.

15. The combination of claim 14 wherein the longitudinal edge of the said one leg is formed to produce a

35 guard lip slightly forward of and below the cutting edge of said blade.

16. The combination of claim 15 including means cooperable between the rearward portion of the other leg and the butt edge surface of said blade for adjusting and clamping said blade in shaving position within the blade holder upon release of said manually-operated element to lock the member and blade against slidable movement.

40 17. The combination of claim 16 wherein the other leg of the blade holder is yieldable with respect to the said one leg to cause tension on the longitudinal surface adjacent the cutting edge of said blade whereby said blade is maintained in engagement with the planar portion of the said one leg during a shaving operation.
